UNITED STATES PATENT OFFICE.

THOMAS L. JACKSON, OF CINCINNATI, OHIO, ASSIGNOR TO FRANK HOLTON & CO., OF CHICAGO, ILLINOIS, A CORPORATION OF ILLINOIS.

TROMBONE.

1,145,145.

Specification of Letters Patent.

Patented July 6, 1915.

Application filed December 11, 1911. Serial No. 664,925.

To all whom it may concern:

Be it known that I, THOMAS L. JACKSON, a citizen of the United States, residing at Cincinnati, in the county of Hamilton and State of Ohio, have invented certain new and useful Improvements in Trombones, of which the following is a specification.

My invention relates to trombones and has for its primary object the provision of a trombone which shall have improved means for tuning and for varying the pitch thereof.

With the above and other objects in view, this invention consists substantially in the combination, arrangement, and construction of parts all as hereinafter described, shown in the accompanying drawings which form a part of this specification and show the preferred embodiment of my invention, and more specifically set forth in the subjoined claims.

Figure 1 is an elevation of a trombone constructed in accordance with the principles of this invention and showing the adjusted positions of the parts in dotted lines and dot-and-dash lines. Fig. 2 is an enlarged longitudinal section of portions of the instrument shown in Fig. 1 and illustrates a partially adjusted position of the parts. Fig. 3 is an enlarged longitudinal section of other portions of the instrument shown in Fig. 1 and illustrates an adjusted position of the parts. Fig. 4 is a view of the parts shown in Fig. 2.

In order to produce the most desirable tones from a trombone it is necessary to eliminate, as far as possible, the interpolation of cylindrical sections in the air passage of the bell member. In order to manufacture a trombone which shall be of practicable use to experienced players it is necessary that the relative positions of the free or flared outer end of the bell member, as well as the handle of the playing slide grasped by the player, remain unchanged, for the reason that the experienced trombone player in the use of the instrument utilizes these relative positions of the playing slide handle and the outer end of the bell member in judging the proper distance to shift the playing slide. Violation of these two essentials of trombone construction must be avoided as far as possible in the making of the instrument, and one of the most serious problems of manufacturers is that of

providing tuning or key changing devices in their trombones while at the same time maintaining the relative positions of the flared end of the bell member and the handle of the playing slide, and likewise producing as little cylindrical section of air passage in the bell member as possible.

My invention discloses means whereby the amount of cylindrical portion of air passage interposed in the tapering portions of the trombone, in the tuning of the device, is greatly reduced from that interposed in the trombones heretofore constructed, which had tuning devices forming part of the bell member itself; and it further discloses means for tuning the trombone, or changing its key, without the slightest change in the relative positions of the handle of the playing slide and the flared outer end of the bell member.

Referring more particularly to the drawing, a bell member 10 is provided with a cylindrical portion 24 secured thereto by means of a fitting 17. The member 17 may be secured to members 10 and 24 by means of solder, brazing or other suitable means in order to form a rigid connection. A collar 14 is secured to the bell member 10 by means of a forked brace comprising members 15 and 16; the member 16 is somewhat curved and secured to fitting 17. The arrangement is such that collar 14 is disposed substantially parallel with the cylindrical portion 24.

The tuning slide or shank 11 is provided at one end with a cylindrical portion 23 fitting in the bore of the member 24. The member 23 is secured to tuning slide 11 by means of a collar 11^a in order to form a rigid connection therebetween. The bores of the tuning slide 11 and member 23 are gradually increased in diameter throughout their length so that the wind passage of the instrument increases in diameter from the end 12 of tuning slide 11 to the outer end of bell 10. At the end 12 of tuning shank 11, is a tubular member 13 slidably fitting in the bore of collar 14 and secured to the tuning shank 11 by means of a collar 18. At one end of collar 14 is a clamp 21 provided with an adjusting screw 22 and adapted to engage the member 13 and secure the tuning slide against movement in the bell member 10 and collar 14.

In this specification, the mouth pipe of 110

the instrument is considered to comprise that portion of the tubing between the mouth piece 31 and the member 13. A cylindrical portion 26 of the mouth pipe is 5 slidably mounted in the bore of member 13 and is secured in a fitting 27 and the latter connected with the playing slide 29 of the instrument. One end of fitting 27 is flared to receive the tapering end 29^a of the playing slide 29, and the latter is provided with brace members 30 and 32 which are of usual construction and adapted to give the playing slide firmness. At the mouth end of the playing slide 29, is a mouth piece 31 of conventional construction. On the end of member 13 opposite tuning slide 11, is a clamp 19 which is provided with an adjusting screw 20 and is adapted to clamp the end of member 13 and secure the members 26 and 13 against relative movement. On the fitting 27 is a handle 34 adapted to facilitate making adjustments of member 26 in member 13.

In describing the tuning or pitch-changing operations of the parts shown, the bell member 10, together with the braces 15 and 16, the collar 14, the clamp 21, and its screw 22, and the extension 24, will be considered as fixed portions of the instrument with relation to which the other portions are movable. In full lines in Fig. 1 is shown the adjustment of the instrument in which the air passage of the instrument is shortest. To lengthen the instrument from this position 30 three methods may be employed. In the first method the mouth piece 31, the playing slide 29, the brace 32, the collar 27, and handle 34, may be considered, together with the bell member 10, the braces 15 and 16, the extension 24, the collar 14, and the clamp 21, as fixed portions of the instrument, and by loosening the clamps 19 and 21, the tuning slide 11, its extension 23, the collar 18, the mouth pipe portion 13, and the clamp 19 may be drawn from the position shown in Fig. 1 in full lines to the position of those parts shown in Fig. 1 in dot-and-dash lines, following which, by operation of the clamping screws 20 and 22, the clamps 19 and 20 may be tightened and the instrument rendered again secure for use.

In the second method of adjustment two movements of the parts are employed. The first movement includes the loosening of the clamp 19 and the shifting of the portion 26 of the mouth pipe, the handle 34, the flared end 27, the brace 32, the playing slide 29, its handle 30, and the mouth piece 31, from the position shown in full lines in Fig. 1 to 55 the position shown for those parts in dotted lines in Fig. 1, which amount of shift is equal to one-half the desired increase of length of the air passage of the instrument. After this first shift the clamping member 60 65 19 is tightened, securing the portion 13 of

the mouth pipe and the parts just shifted into fixed relation. Following this, the second movement is performed, which includes loosening the clamping member 21 and shifting the parts just shifted, together 70 with the parts now attached to them by the clamp 19, namely 13, 18, 11, 11^a, and 23, within the brace 14 and clamping member 21 and in a direction opposite to the direction of shift of the parts in the first movement. The shift of parts in this second movement is in amount equal to the amount of shift of the parts moved in the first movement which leaves the tuning slide 11, the collar 11^a, the extension 23, the collar 80 18, the portion 13, and the clamping member 19 in the position shown in dot-and-dash lines in Fig. 1, and exposes, as is shown in dot-and-dash lines in Fig. 1, both a portion of the extension 23 and a part of 85 the mouth pipe portion 26. To state the movement in a different way, the playing slide of the instrument, together with the mouth piece and the portion 26 of the mouth pipe, have been shifted away from 90 the collar 14 a distance equal to one-half of the desired increase of length, following which these parts have been returned to their first position simultaneously with the movement of the tuning slide 11 and the 95 parts thereto attached in the opposite direction an equal distance.

A third method of adjusting is had by reversing the order of performance of the two movements employed in the second method. 100

In Fig. 2, the parts shown therein are indicated in their positions as the result of the first movement or step in the third method of adjustment of the instrument. This will be evident from the fact that the 105 portion 26 of the mouth pipe is shown in Fig. 2 as telescoped completely within the portion 13 of the mouth pipe, whereas in the complete adjustment of the instrument the portion 26 is partially withdrawn from a 110 fully seated position within the portion 13.

In Fig. 3 is shown the position of parts 11, 23, 24, 16 and 10 in the completed adjustment of the instrument.

Fig. 4 illustrates the parts of Fig. 2 in 115 fully adjusted position.

It is to be noted that in the use of any one of the methods of adjustment described the relation of the playing slide and mouth piece to the bell member 10 is left, after the 120 adjustment, in the same position it occupied at first, and it is to be further noted that only a half of the length added to the air passage of the instrument is inserted in the tapering portions 10 and 11. That is, the 12 only cylindrical portion inserted in the tapering portions is that part of the air passage of the extension 24 exposed after adjustment. The other half of the increased length has been added in cylindrical parts 13

comprising the mouth pipe of the instrument.

It will be seen that in my construction the portion 26 of the mouth pipe telescopes within the portion 13, and that the extension 23 telescopes within the extension 24. This is done in order that the air passing through the instrument may, in each of these instances, go from an air passage of one diameter to the air passage of an increased diameter. Also it is to be noted that the collar 18 contacting with the clamping member 21 limits the relative movement between the collar 14 and the portion 13 of the mouth pipe in one direction; that contact between the clamping member 19 and the collar 14 limits the relative movement between the collar 14 and the portion 13 of the mouth pipe in the opposite direction, and that contact between the annular shoulder 33 and the clamping member 19 limits the insertion of the portion 26 of the mouth pipe within the portion 13 of the mouth pipe.

In the accompanying drawings and in the foregoing specification is set forth the preferred embodiment of my invention, but it is obvious that one skilled in the art may make modifications of the same without departing from the spirit of the invention.

What is claimed as new is:

1. A slide trombone comprising a bell member; a collar secured to said bell member; a tuning slide having a portion adjustably secured in said collar and another portion connected with said bell; and a mouth pipe having one end adjustably mounted in the first-mentioned portion of said tuning slide.
2. A slide trombone comprising a bell member; a collar secured in fixed relation to said bell; a tuning slide having one end portion adjustably connected with the bell member and its other end portion slidably mounted in said collar; a clamp on said collar adapted to secure the last mentioned end portion of the tuning slide in said collar; and a mouth pipe having one

end adjustably connected with said tuning slide.

50

3. A slide trombone comprising a bell member; a collar secured in fixed relation with said bell member; a tuning slide having its end portions slidably mounted in the bores of said collar and bell member; a clamp on said collar adapted to engage said tuning slide and secure the latter in fixed relation with said bell member and collar; a mouth pipe having one end slidably mounted in the bore of one end of the tuning slide; and a clamp on said tuning slide securing said mouth pipe in fixed relation with the tuning slide.

55

4. A slide trombone comprising a bell member; a collar secured to said bell member; a tuning slide having one end slidably mounted in said collar and its other end slidably mounted in said bell member; a mouth pipe having one end slidably mounted in said tuning slide, and clamps engaging said tuning slide and mouth pipe securing said bell member, tuning slide and mouth pipe in fixed relation.

60

5. A slide trombone comprising a tapering bell member having a cylindrical portion at its smaller end; a collar having a cylindrical bore and secured to said bell member; a tapering tuning slide having a cylindrical end portion slidably mounted in said collar and another cylindrical end portion slidably mounted in the cylindrical portion of the bell member; a mouth pipe having one end slidably mounted in the cylindrical end portion of the tuning slide away from the bell member; and clamps engaging the tuning slide and mouth pipe securing said bell member, tuning slide and mouth pipe in fixed relation.

75

In testimony whereof I have signed my name to this specification, in the presence of two subscribing witnesses, on this 6th day of December A. D. 1911.

THO'S L. JACKSON.
